UNITED STATES PATENT OFFICE

EDWARD SCHULTZ, OF CHICAGO, ILLINOIS

DESIGN FOR A TOBACCO ASH RECEPTACLE

Application filed February 1, 1932. Serial No. 42,697. Term of patent 7 years.

To all whom it may concern:

Be it known that I, EDWARD SCHULTZ, a citizen of the United States, residing in Chicago, in the county of Cook and State of Illinois, have invented a new, original, and ornamental Design for a Tobacco Ash Receptacle, of which the following is a specification, reference being had to the accompanying drawing, forming a part thereof.

Fig. 1 is a side view, and Fig. 2 is a top plan view of a tobacco ash receptacle showing my new design.

I claim:

The ornamental design for a tobacco ash receptacle substantially as shown.

EDWARD SCHULTZ.
